CLAIM

The ornamental design for a shoe device as shown and described.

DESCRIPTION

FIG. 1 is a perspective view of a shoe device showing my new design, shown in reduced scale;

FIG. 2 is a perspective view thereof, shown without the shoe for ease of illustration, with one of the pins in uninstalled condition;

FIG. 3 is a perspective view thereof, shown without the shoe for ease of illustration;

FIG. 4 is a top plan view thereof, shown without the shoe for ease of illustration;

FIG. 5 is a bottom plan view thereof, shown without the shoe for ease of illustration;

FIG. 6 is a front elevation view thereof, shown without the shoe for ease of illustration;

FIG. 7 is a rear elevation view thereof, shown without the shoe for ease of illustration;

FIG. 8 is a right side elevation view thereof, shown without the shoe for ease of illustration; and,

FIG. 9 is a right side perspective view thereof, shown in reduced scale.

The broken lines in the figures illustrate the portions of the design that form no part of the claimed design.

1 Claim, 3 Drawing Sheets

Related U.S. Application Data

division of application No. 29/472,421, filed on Nov. 12, 2013, now Pat. No. Des. 748,390.
